DESIGN FOR A JEWELRY CASE OR THE LIKE

Leo Flier, Springfield, Mass.

Application March 25, 1941, Serial No. 99,859

Term of patent 14 years

To all whom it may concern:

Be it known that I, Leo Flier, a citizen of Russia and a resident of Springfield, in the county of Hampden and State of Massachusetts, have invented the new, original, and ornamental Design for a Jewelry Case or the like, of which the following is a specification, reference being had to the accompanying drawing, forming part thereof, in which:

Fig. 1 is a perspective view, from the front or cover, of a jewelry case or the like, showing my design, the jewelry case being illustrated in closed position,

Fig. 2 is a perspective view of the jewelry case from the base thereof;

Fig. 3 is a perspective view showing the top or display surface of the base, the jewelry case being in open position with the base resting on the inverted cover; and

Fig. 4 is a side elevational view of the jewelry case in open position with the cover serving as a pedestal and with the base supported on the pedestal.

The dominant feature of my design resides in the appearance of the display face of the base, substantially as shown.

I claim:

The ornamental design for a jewelry case or the like, substantially as shown and described.

LEO FLIER.
